UNITED STATES PATENT OFFICE.

CHARLES R. PENFIELD, OF DULUTH, MINNESOTA.

FURNACE FOR BURNING GRANULAR FUEL.

SPECIFICATION forming part of Letters Patent No. 469,749, dated March 1, 1892.

Application filed May 28, 1891. Serial No. 394,439. (No model.)

To all whom it may concern:

Be it known that I, CHARLES R. PENFIELD, of Duluth, in the county of St. Louis and State of Minnesota, have invented a certain new and useful Improvement in Furnaces for Burning Granular Fuel; and I do hereby declare that the following is a full, clear, and exact description of the same, reference being had to the drawings accompanying this specification.

My improvement relates to means for introducing a blast of air into the furnace of a steam-boiler and equally distributing the same for burning sawdust, tan-bark, coal-dust, and other granular fuels in an effective manner.

The invention consists in the construction and arrangement of the fire-bed, as herein-after more fully described and definitely claimed.

In the drawings, Figure 1 is a vertical cross-section in line *x x* of Fig. 2, showing three boilers set side by side and exhibiting my improvement. Fig. 2 is a longitudinal vertical section in line *y y* of Fig. 1. Fig. 3 is an enlarged sectional view across the air-trunk and lengthwise of one of the distributing-tubes of the air-feeding apparatus. Fig. 4 is a perspective view of the same.

30 A A A indicate three steam-boilers set side by side and inclosed in suitable brick-work. A greater or less number may be used. B is the furnace or fire-place of the same.

My improvement is as follows: C is a bridge-wall located in the furnace-space transversely of the boilers, the same rising to a suitable height, but leaving sufficient space above the wall and under the boilers for the passage of the draft to the rear of the boilers, as shown.

40 D is an air-trunk located in the fire-space, either at the front or back of the furnace, also extending transversely of the boilers and parallel with the bridge-wall and connected at one end with a blower or other device by which air is blown through the trunk. The trunk is of the sinuous or undulating form shown, being concave under each boiler and convex between them, thereby forming hollows under the boilers, into which the fuel collects and by which a better combustion is maintained, and ridges between the boilers for dividing and spreading the fuel.

E E E are distributing air-pipes attached to the air-trunk and extending crosswise at right angles thereto, reaching nearly to or 55 passing through the bridge-wall, as may be desired. Following the curves of the air-trunk, these air-pipes form hollow beds under the boiler, on which the fuel falls to be burned, and elevations between the boilers to spread 60 the fuel. The top of the air-trunk and also the pipes have small holes *a a a*, through which the air is forced in jets up through the body of fuel that falls on the pipes. The air, being forced in numerous jets, is equally distributed 65 through the whole furnace-space. The air-trunk is preferably made square and the lateral pipes round in cross-section. The masonry is filled around the bottom and between the pipes, leaving only that part exposed in 70 which the holes are located, and as cold air is being constantly forced through they do not easily burn out. The ends of the lateral pipes have small openings *b b*, through which jets of air are blown, the effect of which is to 75 blow out any ashes or other material that may get into the pipes, thus keeping them clear.

G is a trough located above the boilers and transversely of the same and provided with spouts *c c c*, which extend down at the sides 80 of the boilers and open into the furnace-space above the air-pipes. These spouts may be provided with suitable cut-off valves to regulate the flow of the fuel through the same. At one end is a hopper *d*, into which the fuel 85 is fed to be carried to the spouts. H is a conveyer consisting of an endless band or apron resting in the trough and provided with lags, which catch the fuel and carry it forward to the spouts. The apron passes around suitable pulleys, to one of which motion is given to operate the apron. By this means the fuel is fed evenly to the spouts and dropped down between the boilers and upon the air-pipes below. The fire-bed being undulating, the 90 fuel forms in approximate shape, a portion sliding down the sides of the ridges and filling the hollows to an even depth over all the pipes. Thus the fuel is spread of substantially the same thickness throughout the bed, 100 which would not be the case if the bed were flat, the fuel collecting in that case in piles, leaving much of the fire-bed uncovered.

It is found in practice that green or wet

sawdust directly from the log can be readily burned, requiring no special attention, except to regulate the supply.

Having described my invention, I do not claim the fuel-feeding apparatus, as the same is old; but what I claim as new, and desire to secure by Letters Patent, is—

- 5 1. The combination, with a steam-boiler furnace, of the air-trunk D, arranged in sinuous or undulating form, as described, adapted to receive grate-bars, as E, and provided at its top with a series of holes opening upward for the purpose of supplying jets of air to the fuel, as herein shown and described.
- 10 2. The combination, with a steam-boiler

furnace, of a fire-bed consisting of the air-trunk D and lateral connecting-pipes E E, arranged in alternate concave and convex undulations and filled with perforations at the top for the discharge of jets of air through 20 the fuel which falls thereon, as herein shown and described.

In witness whereof I have hereunto signed my name in the presence of two subscribing witnesses.

CHARLES R. PENFIELD.
